Primary Examiner — Karen E Kearney*Assistant Examiner* — Aula Soroush(74) *Attorney, Agent, or Firm* — Paul R. Martin(57) **CLAIM**

The ornamental design for a padded face mask liner, as shown and described.

DESCRIPTION

FIG. 1 is a perspective view of the padded face mask liner of my new design, showing a CPAP mask in broken lines. FIG. 2. Is a front elevational view thereof.

FIG. 3 is a back elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken line showing of the CPAP mask in FIG. 1 depicts environment and forms no part of the claimed design.
